United States Patent [19]

Gillespie et al.

[11] Patent Number: Des. 292,926

[45] Date of Patent: ** Nov. 24, 1987

[54] **COMBINED DATA
TRANSMITTER/RECEIVER MODEM AND
SECURITY MODEM FOR PREVENTION OF
UNAUTHORIZED COMPUTER ACCESS**

[75] Inventors: **Lionel D. Gillespie, Atlanta; Frank B. Golley, IV, Decatur; Phillip J. Snoke, Atlanta; Kenneth D. Timmerman, Smyrna, all of Ga.**

[73] Assignee: **Lockheed Corporation, Calabasas, Calif.**

[**] Term: **14 Years**

[21] Appl. No.: **702,476**

[22] Filed: **Feb. 19, 1985**

[57] CLAIM

The ornamental design for a combined data transmitter/receiver modem and security modem for prevention of unauthorized computer access, as shown and described.

DESCRIPTION

FIG. 1 is a front perspective view of the combined data transmitter/receiver modem and security modem for prevention of unauthorized computer access showing our new design;

FIG. 2 is a front elevational view thereof;

FIG. 3 is a side elevational view thereof, the opposite side being a mirror image;

FIG. 4 is a top plan view thereof;

FIG. 5 is a top plan view thereof; and

FIG. 6 is a bottom plan view thereof.
